UNITED STATES PATENT OFFICE.

JOHN HORRIGAN AND EDWARD N. WALSH, OF JOLIET, ILLINOIS.

RAILWAY-CAR CONSTRUCTION.

1,403,323.

Specification of Letters Patent. Patented Jan. 10, 1922.

Application filed May 21, 1921. Serial No. 471,356.

To all whom it may concern:

Be it known that we, JOHN HORRIGAN and EDWARD N. WALSH, citizens of the United States, residing at Joliet, in the county of Will and State of Illinois, have invented certain new and useful Improvements in Railway-Car Constructions, of which the following is a specification.

Our invention relates to railway cars of the type known as hopper cars, and has for its object to provide an improved car construction of this type in which suitable provision is made for the proper distribution of the stresses imposed upon the car incident to its service.

With this object in mind we have illustrated in the accompanying drawings one embodiment of our invention. In these drawings—

20 Figure 1 is a side elevation.

Figure 2 is a top plan view, and

Figure 3 is a cross section on the line 3^x 3^x of Figure 1 of a side dumping hopper car.

25 Hopper cars as commonly constructed embody a center sill extending throughout the car, and cross sills between the bolsters together with the load enclosing members. In carrying out our invention we dispense with 30 the usual center sill using in place thereof short center sill or draft members 1 extending from end sills 3^a to a point just beyond the inner ends of the trucks. These center sill sections we connect through an

35 improved construction, with an A-shaped floor 7 having its members 7^a diverging downwardly and outwardly from its central and longitudinally disposed apex 7^b, thus lying over the inner ends of the center

40 sill members and extending from one to the other of the body bolsters, indicated at 2. Strut members 8 are disposed at suitable intervals between the floor members 7^a below the line of the center sill members. The

45 load enclosing members of the car in addition to these floor members, comprise vertical end portions 3, the side walls 4 and the inclined end portions 5 which latter slope downwardly and inwardly from the vertical

50 end portions 3 to a point 3^a beyond the inner ends of the trucks. Extending across the ends of the A-shaped flooring sections are flanged members 3^b suitably connected to the A-shaped flooring members. Extending

55 across these floor members at the inner

end of each center sill member, said flanged member 3^b and a cover plate 3^d rests upon and is secured to the members 3^b and 3^c at its front and rear margins, while its lateral dimension is sufficient to bridge the space 60 between and have its lateral margins secured to the under sides of the floor members 7^a. The inner end of the center sill member is secured in any suitable way to the support formed by the members 3^b, 3^c, 3^d and 65 said center sill member is further secured to the floor members through the medium of the flanged member 3^b extending across the end of and secured to the A-shaped floor and above the center sill to which it is 70 also secured. It will thus be seen that the plate 3^d lies in a substantially horizontal position and extends longitudinally of and is secured to one horizontal face of the draft sill while the flanged member 3^b extends 75 transversely of and is secured to the opposite horizontal face of the draft sill. Thus there is established a rigid draft connection between the center sill section and the A-shaped floor section which will efficiently 80 transmit the buffing and pulling loads; and it will be noted that the stresses are largely imposed edgewise upon the cover plate 3^d and by said plate distributed to the A-shaped floor section from the four marginal members of the plate.

Between the trucks outwardly swinging doors 9, pivoted at their upper edges below the sides 4, permit the discharge of the lading from the downwardly and outwardly sloping floor members 7^a. It is customary in cars of this type, which are provided with high vertical sides, to tie the sides together at the top by horizontal cross rods, in order to prevent the outward bulging of the sides, 90 due to the pressure of the load. It is also customary to provide such cars with stakes attached to the sides and to the cross beams of the underframe. But according to the present invention, in order to provide a rigid 100 attachment of the sides to the floor of the car and to prevent the outward bulging of the sides usually compensated for by the aforesaid cross rods at the top, we have provided gusset plate members 10 which extend 105 downwardly and inwardly from points near the top of the sides to points well above the middle and sufficiently near the apex of the sloping floor members 7^a to rigidly stay the upper margins of the side walls. For con- 110

venience of fabrication these members 10 may be made in sections 10^a and 10^b rigidly secured together as indicated at 10° and secured to the floor members 7^a by flanged members 10^a. These members 10 as shown extend inwardly from the sides for a considerable distance along the floor and thus act to tie the upper portions of the sides to the inner portion of the floor and perform the 10 functions not only of the horizontal cross rods above described but also of the usual side stakes. The outward strains at the top of the sides, therefore, due to the load, are resisted by the members 10 and transmitted 15 to the inclined floor. These members at the same time form a support for the sides of the car.

The inclined floor members are supported on the center sill members at the ends of 20 the flooring through the medium of members 12 which are bent to conform to the shape of the apex of the floor and which are connected to the center sill members by angle irons 11.

It will be seen that in our improved construction we have not only provided a car in 25 which the usual center sills and the usual cross beams are dispensed with, and replaced by an A-shaped floor member extending between short center sill sections, but we have 30 provided novel constructions whereby stub sills at the ends of the car are connected to this A-shaped floor member rigidly and in a manner that efficiently distributes to said floor member the stresses imposed upon the 35 car when in service.

We claim:

1. In a dump car having an A-bottom and a draft sill at the end thereof, means for establishing draft and buffing connection between 40 said sill and bottom, comprising a substantially horizontal plate extending longitudinally of and connected with one horizontal face of said sill and having margins connected with said bottom.
2. In a dump car having downwardly and laterally inclined floor members, and a longitudinal draft sill at the end thereof, means for establishing draft connection between 45

said sill and bottom members comprising a substantially horizontal plate extending 50 longitudinally of and secured to one horizontal face of said sill, and transverse members bridging the space between and secured at their ends to said floor members and secured to forward and rearward edges of said 55 plate.

3. In a dump car having downwardly and laterally inclined floor members, and a longitudinal draft sill at the end thereof, means for establishing draft connection between 60 said sill and bottom members comprising a substantially horizontal plate extending longitudinally of and secured to one horizontal face of said sill, and transverse members bridging the space between and secured 65 at their ends to said floor members and secured to forward and rearward edges of said plate; said plate having longitudinally extending edges thereof also connected with 70 said bottom members.

4. In a dump car having an A-bottom and a draft sill at the end thereof, means for establishing draft and buffing connection between 75 said sill and bottom, comprising a substantially horizontal plate extending longitudinally of and connected with one horizontal face of said sill and having margins connected with said bottom, and a member extending transversely across the other horizontal face of said sill and bridging the 80 distance between and secured at its ends to said bottom.

5. In a dump car having inclined bottom members meeting at a longitudinal apex, and side members above said bottom members; tension stay braces comprising gusset plates extending approximately the full vertical dimension of the side members and having inclined inner edges extending from the upper margins of the side members 85 downwardly and inwardly to the bottom members at points adjacent the apex thereof. 90

Signed at Joliet, Illinois, this 29th day of April, 1921.

JOHN HORRIGAN.
EDWARD N. WALSH.
